his attorney

UNITED STATES PATENT OFFICE.

EDWIN E. SLICK, OF PITTSBURGH, PENNSYLVANIA.

METHOD OF MAKING COLD-ROLLED ARTICLES.

Application filed April 21, 1922. Serial No. 555,867.

Figure 1 is a sectional side elevation of one form of machine adapted for carrying out my process; and

Figure 2 is a plan view of the rollers and cage therefor.

My invention relates to the class of cold-rolling and is designed to provide a new method and new article of manufacture in this class of work. Heretofore, cold rolling had been carried out by ordinary rolls, through which the work, such as shafting strips, etc., is passed, while cold, to impart the desired dense smooth cold-rolled surface.

My invention is designed to widen the field for cold rolling and to provide articles, such for example, as tapered disks for wheel bodies, having the highly desirable cold-rolled surface either throughout the surface or in annular or circular zones thereof, the cold rolling being carried out in such circular or annular zones.

In carrying out my process, I preferably employ a work or blank support on which the blank is laid, and employ a thrust member which is forced toward the blank during the operation and employ between the members a system of rolling elements which move in substantially annular or circular paths over the blank. I thus impart a highly desirable cold-rolled finish to the surface portion of the blank, and if desired, to both surfaces at the same time by employing rollers on the work-supporting member, as well as between the blank and the thrust member, as illustrated in Figure 4 of my Patent No. 1,423,268, of July 18, 1922.

I will now describe one machine for carrying out my invention, the preferred type of machine being shown in my patent referred to. This patent shows different types of machines, of which I have selected the first type as an example.

In the drawings, the blank, which may be a disc or blank of any desired shape cut from a plate or sheet, may be carried on a work support 2. In the type of operation chosen for this example, this blank is spread out and tapered from the central portion toward the edge portion, preferably in the same general type of machine, and while the blank is heated in the ordinary manner. If the blank is formed in this manner, it is thereafter rolled in the same machine while cold to give the

cold-rolled finish. In the type shown, the work support is slightly dished and the blank is cold rolled by a plurality of rollers 3, pressed against the blank by thrust plate 4, which is rotated relatively to the work support 2. The rollers 3 which are preferably solid and imperforate are shown as loosely mounted in a cage, indicated generally by numeral 5. This cage is shown as comprising two semicircular blocks 6, the inner edges of which are concave to fit around and guide the rollers 3. A band 7 fits around the two blocks 6 and holds them together. The thrust plate 4 is mounted on a rotating head 8, and is preferably made of hardened steel to withstand the wear from the rollers. The thrust plate 4 and cage 5 are held on the head 8 by means of rings 9 and 10, which are supported on the head 8 by means of bolts 11. The ring 9 has countersunk bolt holes for the flanges 12 on the bolts which support it. Threaded on the lower ends of the bolts 11 are nuts 13, which support the ring 10. By removing the nuts 13, the ring 10 can be taken off and the cage 5 released. Then, if it is desired to take off the thrust plate 4, it can be taken off by loosening the nuts 13^a.

A centering stud 15 centers the thrust plate 4 on the head 8 and a pin 16 holds the thrust plate and head against relative rotation. The cage 5 is held so that it can freely rotate on its supporting ring 10. Sufficient clearance is provided between the cage 5 and the work so that the cage may turn freely relative thereto.

The work-supporting plate 2 is made of hardened steel or cast chilled iron and is supported on a head 17. It is centered on the head by means of a hollow stud 18 and is prevented from rotating relatively to the head 17 by means of a pin 19. A spring-pressed stud 20 projects through the work support 2 and into the hole drilled in the center of the disk for the purpose of centering the disk on the work support. The blank may be solid, in which case the centering stud will not be needed.

During the cold-rolling operation, the two heads 8 and 17 are forced against each other and relatively rotated so that the rollers 3 roll around in circular or annular paths over the plate. The rollers are frictionally driven by contact with the thrust plate and the blank

which rotate relatively to each other. As shown in the drawings, the rollers at each side of the axis of rotation are preferably so spaced that the rollers at one side will not track with the rollers on the other side. This causes the rollers to cover all portions of the annular zone acted upon and give a smoother and better finish.

As shown in the drawings, the two series 10 of rollers on opposite sides of the center are separated by a spacer 26, formed on the blocks 6 of the roller-supporting cage. This spacer block 26 is a little to one side of the axis of rotation. As shown in the drawings, there 15 are nine rollers at the left of the axis of rotation and eight at the right. This arrangement insures that the radius from the axis of rotation to the point of separation between two rollers at one side of the center is equal 20 to the radius from the axis of rotation to the middle of a roller on the opposite side.

The end faces of the rollers 3 are preferably slightly bulged at the center, this bulging being somewhat exaggerated in the 25 drawings for the purpose of illustration. The rollers therefore contact with each other only in their central portions, so that friction between them is reduced. Each roller is permitted to assume its own speed, the speed 30 of the rollers, of course, differing among themselves.

It is found to be advantageous in work of this character to employ rollers of small diameter, because the small diameter roller has 35 a smaller surface of rolling contact with the work. Therefore, the thrust of the rollers against the work is concentrated in a smaller area and the blank rolled out more efficiently than would be the case if larger diameter 40 rollers were used. Since the rollers 3 are subjected to a considerable thrust, it is desirable that they be made solid. The use of the cage 6 permits small solid rolls to be used. The cage holds the rollers in alignment and prevents any roller from moving 45 sidewise out of its end to end alignment with the other rollers. With the cage it is unnecessary to bore the rolls to receive any shaft for holding them in alignment or supporting them, thus permitting the rolls to be 50 made solid and of a maximum strength.

The head 8 is mounted in the cross pedestal of the machine so as to rotate. As 55 shown in the drawings, the head 8 is provided with a vertical shaft 30, extending through a bushed bearing 31, while a work plate 32 forms a vertical thrust bearing for the head 8. The bearings are lubricated 60 through the oil groove 33. Splined to the head of the shaft 30 is a gear 34, which is driven by a pinion 35. The pinion 35 is carried on a shaft 36, which, at its lower end, has a bevel gear 37, driven by a bevel gear 38 on a shaft 39, which is driven through the 65 reduction gearing 40 by electric motor 41.

The head 17, which carries the work support 2, is vertically movable and is forced by hydraulic pressure against the rollers 3. The head 17 has a plunger 45, which enters a hydraulic cylinder 46, supplied with fluid 70 under pressure through a pipe 47. An adjustable collar 48 on plunger 45 limits its upward movement. A pin 51 extends from the head 17 into a stationary part of the machine to prevent the head 17 from rotating. 75

In carrying out my improved method with this machine, the blank while cold lies on the work support 2, and fluid is admitted under pressure to the hydraulic cylinder so 80 as to force the work support and the blank against the rollers. The head 8 with the thrust plate 4 is rotated as the relative end thrust is imparted, so that a fine cold-rolled surface is imparted to the blank or to the circular or annular zones thereof, which are 85 acted upon by the rollers.

The cold-rolled surface is thus imparted to the upper face of the blank, and if a similar surface is desired for the other face, the blank may be turned over and the operation 90 repeated; or the type of machine may be changed and rollers employed to carry the blank, in which case, the blank will be cold-rolled on both faces at the same time. 95

It is obvious that the blank may be hot-rolled to the desired shape in this machine, before it is cold-rolled, or the blank may be given its shape in any desired way previous 100 to this cold-rolling operation. The type of machine employed may be widely varied, and many other changes may be made without departing from my invention. 105

The advantages of the invention are apparent, since a highly desirable annular or circular cold-rolled surface may be imparted 105 to articles, such as wheel disks, circular saws, etc. -

I consider myself the first to make a cold-rolled disk of varying thickness, whether rolled by circular or annular rolling or not. 110

I claim:

1. In the method of cold-rolling circular articles, the steps comprising supporting the article to be rolled and subjecting at least one side face thereof to the substantially uniform action of independently movable floating rollers traveling concentrically over the article. 115

2. In the method of cold-rolling circular articles, the steps comprising supporting the article to be rolled and subjecting at least one side face thereof to the action of a plurality or series of independently movable rollers traveling concentrically over the article with the paths of the rollers in one series 120 staggered relatively to the paths of those of the other series. 125

3. In the method of cold rolling circular articles, the steps comprising supporting the article to be rolled and subjecting at least one 130

side face thereof to the action of independently movable solid rollers travelling concentrically over the article.

4. In the method of rolling circular articles, the steps comprising supporting an article to be rolled, providing roller supporting means in spaced relation to the article, posi-

tioning rollers intermediate the article and supporting means, and causing said rollers to travel concentrically over the article with independent movement. 10

In testimony whereof I have hereunto set my hand.

EDWIN E. SLICK.
